UNITED STATES PATENT OFFICE.

CLIFFORD A. PETTIS, OF PAINTED POST, NEW YORK.

COCK OR FAUCET.

Application filed May 12, 1922. Serial No. 560,318.

To all whom it may concern:

Be it known that I, CLIFFORD A. PETTIS, a citizen of the United States, residing at Painted Post, in the county of Steuben and State of New York, have invented certain new and useful Improvements in a Cock or Faucet; and I do hereby declare the following to be a full, clear, and exact description of the invention, such as will enable others skilled in the art to which it appertains to make and use the same.

This invention relates to a valve, faucet or cock principally adapted for use in connection with lavatories and bathtubs.

The principal object is to provide a valve of this nature which will be self-closing, as through pressure of water, expansion of a spring, or both, after actuation and release.

It is aimed to generally improve and render a device of this type more efficient and to produce one which is self-closing, has a compression action, may have a single handle to control a plurality of valves, one having a single body or casing through which either hot or cold water may pass under control of said valves, and one having novel plugs attachable to the casing and adapted to mount the water control valves and as well serve as the connecting means between the casing and the water supply pipes.

With the above and additional objects in view, the invention has been embodied in preferred forms as hereinafter described and illustrated in accompanying drawings.

In said drawings:

Figure 1 is a view of the improved sink faucet partly in front elevation and partly in longitudinal section;

Figure 2 is a plan view;

Figure 3 is a cross sectional view on the line 3-3 of Figure 1; and

Figure 4 is a cross sectional view on the line 4-4 of Figure 1.

Like reference characters designate like or similar parts in the different views.

Referring specifically to the drawings and first to the device of Figures 1 to 4, the embodiment is preferably adapted for use as a sink faucet but of course it is obvious that it may be applied to any other suitable use. The faucet is shown at A which may have a hollow casing 10 from which a discharge spout or neck 11 extends as usual. An operating stem 12 is turnably mounted in the casing 10, having its lower end journaled

in a bearing 13 within the casing and in a suitable cap or closure 14 screw threaded to the casing as at 15. Externally of the body, a suitable handle 16 is rigidly secured to the stem 12. The handle may be of any suitable construction, but preferably has the words "Hot" and "Cold" delineated thereon to inform the user as to the direction of turning for hot and cold water, respectively.

Screw threaded into the casing 10 as at 17 are pipes or plugs 18 having shoulders 19 to abut the casing. Slidably mounted in bores or passageways 19^a longitudinally of the plugs 18 are valve stems or rods 20, preferably of less diameter than the passageways 19. The rods 20 also slidably pass through suitable heads 21, in pipes or plugs 18, and disposed against the inner ends of the plugs 18. The inner ends of the stems 20 preferably have enlargements 22 thereon and between the enlargements 22 and heads 21, expansive coil springs 23 are provided about the stems. Said springs 23 urge the stems 20 toward the operating stem 12.

Extending laterally from the operating stem 12 is a lug or bit 24 which is engageable selectively against either enlargement 21 in order to slide either valve stem 20.

The outer ends of the plugs 18 are formed into valve seats 25 and suitably secured on the stems 20 as by means of metal disks or washers 25^a and nuts 26, are flexible washers or valves 27 which are engageable with said seats 25 to close them and urge them into closing engagement with said seats by the springs 23.

In order to supply water to the passageways 19^a, elbow pipes are provided as at 28, being secured in place as by means of hollow nuts 29 screw threaded at 30 on to the plugs. These hollow nuts 29 have flanges 31 which engage enlargements 32 on the elbow 28 and which may have a ground joint with the nuts in order to form a water tight joint. These elbows 28 preferably extend from the back wall of a sink and connect one with the hot water pipe and one with the coil water pipe in the rear thereof although it is obvious that the manner of connection of the pipes 28 or their place of connection may be varied within the spirit and scope of the invention. Plates or collars 33 may be screw threaded on the pipes or elbows 28 for contact against the sink back. In addition, a similar plate or collar as at 34 may be screw threaded at 35 on the

casing 10 in order to be screwed against the said sink back.

In operation, the handle 16 may be turned in either direction. By turning in one direction, it engages one of the heads 21 and by turning in the other direction it engages the other head 21, whereby the valve washers 27 are unseated and water, hot or cold, according to the particular valve 10 opened flows from one of the elbows 28, past the valve 27, into passageway 19^a, into casing 10 and discharging therefrom through the spout 11. It will be realized that as the handle 16 turns, it accordingly turns the stem 12, the latter rotating in the bearing 13 and having its lug 24 engage a head 21, pressing the stem 20 slidably inwardly, compressing the spring 23 so that when the handle is released, the pressure of water against the valve 21 will seat it, assisted by the spring 23, thus urging the valve stem 20 to normal position and causing the head 21 to contact with the lug 24 and restore the stem to a normal position. As a result, the valve 25 is self closing.

It is to be understood that the invention is to be considered as a valve broadly and not as a sink faucet or basin cock only since the disclosure of the latter uses is to be taken by way of example only. Also changes in the details, arrangements and combination of the parts may be resorted to within the spirit and scope of the invention.

I claim as my invention:—

35 1. A cock or faucet having a casing, alined pipes attachable thereto and attachable in communication with different sources of supply, heads integral with and adjacent the inner ends of said pipes, valves for which 40 the outer ends of said pipes constitute seats,

stems detachably carrying and extending from said valves through said pipes and said heads, enlargements at the inner ends of said rods, expansive springs on said stems abutting said heads and said enlargements to urge seating of the valves, and an operating member having a part disposable intermediate said enlargements and selectively engageable with them to impart displacing movement to the valves. 50

2. A cock or faucet having a casing, alined pipes attachable thereto for communication with different sources of supply, heads integral with and adjacent the inner ends of and in the bores of said pipes, valves for which the outer ends of said pipes constitute seats, stems detachably carrying and extending from said valves through said pipes and said heads, enlargements at the inner ends of said rods, expansive springs 55 on said stems abutting said heads and said enlargements to urge seating of the valves, an operating member movable from the casing independently of said rods and valves, said operating member having a part disposable intermediate said enlargements and selectively engageable with them to impart displacing movement to the valves, a bearing for the lower end of the operating member and within said casing, and hollow nuts 60 threaded to the pipes adjacent their outer ends and constituting chambers for said valves. 65

In testimony whereof I affix my signature in presence of two witnesses.

CLIFFORD A. PETTIS.
